EUGENE M. BOURNONVILLE, OF JERSEY CITY, NEW JERSEY.

INTERNAL-COMBUSTION ENGINE.

1,096,094.

Specification of Letters Patent. Patented May 12, 1914.

Application filed February 14, 1912. Serial No. 677,535.

To all whom it may concern:

Be it known that I, EUGENE M. BOURNONVILLE, a citizen of the United States, and resident of Jersey City, in the county of 5 Hudson and State of New Jersey, have invented certain new and useful Improvements in Internal-Combustion Engines, of which the following is a specification.

The general object of the invention is to 10 provide certain improvements, more particularly for engines of the four cycle type, tending to simplify and cheapen the construction and improve the operation thereof.

The invention relates more particularly to 15 those provisions in internal combustion engines that admit the fresh charges to the cylinders and permit the removal of the burned or exhaust gases, the object being to provide improved valve structures, capable of operation 20 by simple means, whereby exact and noiseless functioning is secured, durability is increased, and cost, both initial and upkeep, may be reduced.

A valve structure is employed comprising 25 tubular intake and tubular exhaust conduits with ports, inside a casing communicating with the cylinders. By utilizing movable conduits as a valve, and more particularly when such conduit valve is rotated to open 30 and close the ports at the proper times, very desirable results may be secured. By properly lubricating the surfaces of the relatively moving parts, so as to preserve a film of oil therebetween, and, in the case of the exhaust 35 conduit, by the employment of cooling or heat-non-conducting provisions to avoid material relative expansion of the casing and outer part of the valve, a nice fit without sticking is insured. The intake and exhaust 40 conduits are combined in one structure, the exhaust conduit being inside the intake conduit. In this way the gases in the intake conduit serve to keep the outer wall of the valve comparatively cool, by preventing or 45 minimizing the transmission of heat from the inner to the outer tubes. In addition to this, means are interposed between the conduits, as for example, a gas or air space, which not only contributes to preventing 50 overheating of the outer wall of the valve but also guards against overheating of the intake gases. The intake gases pass from the interior of the outer or intake conduit of the valve through ports spaced apart longitudinally of the valve and formed directly

through the outer part thereof in positions to register with the cylinder ports at the proper times. The fresh gases are admitted to the intake conduit or space of the valve through the sides thereof at a point or 60 points between or alternating with the aforesaid ports. Provisions are made to allow for relative expansion movements of the parts of the valve. While best results will be secured by combining all these features, desirable constructions may be produced by utilizing a less number or different combinations thereof. These and other features of the invention will now be more particularly described, with reference to the 65 preferred and illustrative form of construction shown in the accompanying drawings.

In the said drawings: Figure 1 is a vertical longitudinal section through a two cylinder engine having a combined intake and 70 exhaust valve comprising tubular conduits; Fig. 2 is a vertical transverse section of a cylinder and the valve in its casing, the cylinder being about to take in a new charge; and Fig. 3 is a similar view, the cylinder being about to exhaust.

The engine may comprise any suitable number of cylinders and pistons, of any suitable construction. Preferably the cylinders are disposed parallel.

The cylinders herein shown are designated 1, the pistons 2 and the crank shaft 3. The cylinders are provided at the top with ports 4, there preferably being a single port for each cylinder. The illustrative construction 90 herein shown employs a rotary, cylindrical, combined intake and exhaust valve, designated 12, which fits inside a cylindrical valve casing 5 disposed longitudinally and preferably centrally over the tops of the cylinders. The casing 5 may be cast with the cylinders 1, or the casing may be formed and secured to the cylinders in any suitable manner. The casing is preferably directly over or in contact with the water-jackets 6, for 95 cooling. The end plates 7, 8 of the casing 5 may be formed separately and bolted thereon as shown. Inlet and discharge means are provided. Preferably, the inlet means includes an annular enlargement or chamber 9, extending a greater or less distance around the casing, and having an inlet connection or connections for the fluids or gaseous mixture. An inlet connection 10 is shown, which is designed to communicate with a 100 105 110

carbureter (not shown). There may be any suitable number of inlets, 9, 10; and they may be nearer to or more remote from the cylinder ports 4. The discharge means preferably leads from one end of the cylindrical casing 5. For this purpose a pipe or conduit 11 may be formed on or secured to the plate 8, which is provided with a corresponding opening therethrough, this pipe leading to 10 or constituting part of the muffler.

The casing 5 houses a cylindrical valve structure. I have illustrated a rotary valve comprising concentric tubes or hollow cylinders, the whole being designated 12. This 15 valve comprises both an intake conduit 13 and an exhaust conduit 14. The intake passage is annular in cross-section and surrounds the exhaust conduit. The intake conduit communicates with the inlet ring 9 by 20 any suitable number of apertures 15 through the outer side wall of the valve. It also has ports or openings 16 through the outer side wall of the valve, these ports being positioned to register with the cylinder ports 4 25 at the proper times. The exhaust conduit 14 is provided with radial ports or passages 17, one for each cylinder, disposed in circumferential alinement with the ports 16, and positioned so as to register with the 30 cylinder ports 4 at the proper times. The ports or passages 17 extend through the annular intake gas space 13, and preferably constitute the means for securing the inner and outer parts of the compound valve together. One end of the exhaust conduit 35 14 of the valve is shown closed and the other end open and projecting into the discharge passage 11. Suitable means are provided for insuring a tight joint between the intake and exhaust gases.

Oiling means, indicated at 18, are provided for supplying a film of oil between the side walls of the casing 5 and the rotary valve, thereby guarding against sticking 45 and rendering the parts gas-tight at these regions. This rotary valve may be driven by the simplest means, preferably directly from the crank shaft. It is shown as provided at one end with a shaft 19 which projects through a bearing and stuffing-box on the end plate 7 and may be provided with any suitable form of gear wheel, indicated at 20. It will be obvious that the wheel 20 may be a sprocket wheel connected by a 50 chain with a sprocket wheel on the crank shaft, or it may be a spur gear connected by a chain of gearing with the crank shaft, or it may be a bevel gear, connected with the crank shaft by means 55 of an intermediate shaft with bevel gears meshing therewith and with a bevel gear on the crank shaft. In any case the gearing is such that the valve is driven in proper ratio to the crank shaft. It will be 60 65 a simple matter to adjust the driving con-

nection in such manner that the operation of the valve is timed exactly in accordance with the positions of the cranks.

Heat-insulating means are preferably provided between the intake and exhaust conduits 13 and 14. In the particular construction illustrated an annular air or gas chamber 21 extending substantially the full length of the valve is shown separating the two conduits, the central part or tube of the valve being preferably double-walled for this purpose. The inner and outer parts of the valve should be so connected that the expansion of the inner part or parts will not cause breakage. The particular preferred construction shown will be detailed hereinafter.

The operation will now be briefly described. The intake conduit or gas space 13 is always in communication with the carbureter. As the piston in any cylinder commences its suction stroke, the corresponding port 16 begins to communicate with the port 4, and the area of communication increases as the piston travels more rapidly, until the ports are in full register when the piston has completed half its stroke. Thereafter, the area of communication between the ports 16 and 4 decreases, as the speed of the piston grows slower, until the communication 95 is entirely cut off when the piston has reached the end of its stroke. The port 4 is now closed by the blank wall of the rotary valve. The piston now executes its compression stroke, the charge is ignited, 100 and the piston performs its working stroke, the port 4 still being closed by the blank wall of the valve. As the piston starts upward on its scavenging stroke, the port 17 commences to register with the port 4, and 105 comes into full registry, and then progressively cuts off, as the piston reaches mid-position and then approaches the end of its stroke. The burnt gases are thus driven through the port 17 into the exhaust conduit 110 14, whence they are discharged through the muffler or into the air as the case may be. The outer wall of the valve is kept cool by means of the intake gases in the conduit or space 13 surrounding the exhaust conduit. 115 A proper degree of insulation between the inner and outer ports of the valve insures that the outer wall thereof will not expand more than the valve casing, or to so slight a degree that there will be no danger of 120 sticking in the casing; it also guards against overheating of the intake gases.

The inlet 9, 15 to the intake space 13 of the valve is at the side of the valve and located between the ports 16, which admit the fresh gases to the cylinders. Consequently, the flow of fresh gases in the intake conduit alternates, to left and right, according as one port 16 or the other communicates with the corresponding cylinder port. In 125

this way, the jacketing effect in the several portions of the valve adjacent the several cylinders is equalized; and, moreover, the charges enter the several cylinders at the same temperature, that is to say, the charges which enter one cylinder are not heated more or less than the charges which enter another cylinder. Causing the fresh gases to enter the valve through openings, as 15, distributed around the exhaust conduit, is desirable as promoting to some degree the uniformity of conditions. It will be obvious that these principles of construction are just as applicable to an engine having four 15 or any number of cylinders, as to one having two. In fact, two cylinders are shown merely for simplicity.

The manner of making the combined valve 12 may be widely varied. The outer 20 part or tube of the valve is preferably a casting 22 open at its ends and provided with internal end flanges 23. The inner tubular structure is preferably made of seamless tubing. The conduit 14 is shown as formed of two tubes 24 placed end to end, with a suitable space between their ends to allow for longitudinal expansion. Their inner ends may be inclosed in a sleeve 25, also of tubing. The closed end wall 26 of the conduit 14 is 25 preferably a circular plate welded around its periphery to the end of the tube 24. The tube 27, affording the air or gas chamber 21, is shown secured to the tubes 24, and holding the latter in proper relation, by means of 30 rings 28, which are welded to the tubes 27 and 24. The tubes 29 which form ports or passages 17, and which secure the inner and outer parts of the valve together, are preferably welded to the tubes 24 and 27, and are 35 screwed into tapped openings in the outer wall 22. The screw connections between the radial tubes 29 and the outer part 22 of the valve afford enough play to allow for the slight radial movement of the tubes 29 due 40 to the expansion of the heated central part of the valve. While the tubes 29 forming the passages 17 are shown integral, they may be made of two pieces which are welded together during the operation of assembling, 45 as on the transverse dotted lines 34. Clearance is provided, as shown, at the right-hand end of the inner part of the valve, to allow for longitudinal expansion. At the left-hand end, packing 30 is interposed between 50 the ring 28 and a flange ring 31 bolted to the flange of the outer part 22 of the valve. This packing affords a tight joint at this place, while permitting the necessary longitudinal expansion movement.

55 32 is a separate ring, somewhat thicker than the flange ring 31, interposed between the flange 23 and the plate 8, and acting as an end thrust bearing. The shaft 19 is shown as formed on a plate or disk 33 bolted 60 to the right-hand flange 23.

While the foregoing specific details of construction are regarded as desirable, it will be understood that numerous other forms may be produced accomplishing the same results by equivalent means.

An obvious expedient to compensate for wear and secure a proper fit at all times between the valve and valve casing would be to split the latter longitudinally and to draw its edges together against shims by means of 75 bolts.

What I claim as new is:

1. In an internal combustion engine, the combination with a plurality of cylinders and pistons therein, and a valve casing, of a 80 rotary tubular valve in said casing embodying a longitudinal exhaust conduit surrounded and jacketed by a longitudinal intake conduit, both conduits having ports for communicating with the interiors of the cylinders at the proper times, the exit ports of the intake conduit being spaced apart longitudinally of the valve and affording direct passage for the charges through the outer part of the valve from the interior of said conduit to the cylinders, said intake conduit having an inlet for fresh gases through the side of the valve and intermediate the said exit ports.

2. In an internal combustion engine, a tubular cylindrical valve embodying an exhaust conduit surrounded and jacketed by an intake conduit with heat-insulating means between, said conduits being provided respectively with discharge and inlet means, 95 and both having ports for communicating with the interior of the cylinder at the proper times.

3. A tubular valve for internal combustion engines comprising a tubular exhaust 100 conduit having double walls spaced apart to afford a heat-insulating chamber, the inner wall in contact with the hot gases being transversely severed to permit of expansion and contraction.

4. A tubular valve for internal combustion engines comprising a tubular exhaust conduit having double walls spaced apart to afford a heat-insulating chamber, the inner wall in contact with the hot gases being 105 transversely severed to permit of expansion and contraction, and a sleeve fitting over the severed portion of said inner wall.

5. A tubular combined intake and exhaust valve comprising concentric intake and exhaust conduits, the exhaust conduit being surrounded by the intake passage and having double spaced walls affording a chamber to prevent overheating of the intake 110 gases.

6. In an internal combustion engine, a cylindrical tubular valve combining intake and exhaust and comprising inner and outer conduits, the exhaust conduit being surrounded and jacketed by the intake conduit,

- one having discharge means and the other inlet means, the outer conduit having lateral ports for communicating with the cylinder or cylinders, and tubes connecting the conduits and having provision for radial play so as to allow for radial expansion movements, said tubes affording communication between the inner conduit and the cylinders at the proper times.
10. A tubular combined intake and exhaust valve comprising an exhaust conduit and an intake conduit surrounding the exhaust conduit, and radial tubes for admitting the exhaust gases to the exhaust conduit, said tubes being welded to the wall of the exhaust conduit and screwed to the wall of the intake conduit.
15. A tubular combined intake and exhaust valve comprising an exhaust conduit and an intake conduit surrounding the exhaust conduit, and radial tubes for admitting the exhaust gases to the exhaust conduit, said tubes being welded to the wall of the exhaust conduit and screwed to the wall of the intake conduit and being formed of two tubular sections with their ends welded together.
20. A valve for internal combustion engines, the combination with a tubular intake closing part provided with a lateral port or ports, of a combined intake and exhaust structure movable therein and having laterally-ported longitudinal intake and exhaust passages, one surrounded by the other, means between said passages to retard the transfer of heat from the exhaust passage to the intake passage.
25. A rotary valve for internal combustion engines, comprising a cylindrical body having a central exhaust chamber open at one end and closed at the other end and also having a laterally-open port, the valve body also having an inlet chamber surrounding the exhaust chamber and opening through one end of the valve body, and said body
- also having an air chamber intermediate the exhaust and inlet chambers.
30. A rotary valve for internal combustion engines, said valve having a central exhaust chamber, and a plurality of other chambers between the exhaust chamber and the outer wall of the valve, the walls of said chambers being rigidly connected to form a single rotatable valve body.
35. A rotary valve for internal combustion engines, comprising a rotary cylindrical body having a central exhaust chamber open at one end, an admission chamber surrounding the exhaust chamber and open at the opposite end, and an air chamber intermediate the exhaust and admission chambers.
40. A rotary valve for internal combustion engines, comprising a rotary cylindrical body having a central exhaust chamber open at one end, an admission chamber surrounding the exhaust chamber and open at the opposite end, and an air chamber intermediate the exhaust and admission chambers.
45. In valve mechanism for internal combustion engines, the combination with a pair of engine cylinders, of a fixed valve-seating cylinder communicating with an admission chamber, and also with an offtake, and having a port leading to each of the engine cylinders, and a rotary valve in said valve-seating cylinder, said valve having concentric walls forming an inlet chamber having ports adapted to be alternately brought into register with the ports leading to the engine cylinders, the valve also having a central exhaust chamber surrounded by the inlet chamber and communicating with the offtake and having ports adapted to be brought into register with the port leading to either engine cylinder, and there being in addition to the inlet and exhaust chambers an air chamber intermediate the exhaust and the outer walls of the valve.

In witness whereof I have signed my name in the presence of two subscribing witnesses.

EUGENE M. BOURNONVILLE.
